WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY

DUO STROKE SERIES FOR SHAPING MACHINES

Application filed June 27, 1930. Serial No. 464,383.

This invention relates to shaping machines and it has as an object so to improve the mechanism which effects reciprocation of the ram and movement of the work table that the efficiency of the machine will be greatly increased. More specifically stated an object of this invention is, without resorting to complicated mechanisms, materially to increase the number of available speeds of reciprocation of the ram and also to extend those speeds over a wider range.

Conventional shaping machines are usually provided with about eight speeds of ram reciprocation, those speeds being arranged in geometric progression and ranging from about 9 strokes to 118 strokes per minute. It will thus be perceived that there is necessarily a substantial difference between the adjacent speeds, this difference usually being in the neighborhood of fifty per cent of the lower rate. For example, in conventional shaping providing eight stroke rates the two slower rates have been approximately 9 and 13½ strokes per minute while the two fastest rates have been approximately 80 and 118 strokes per minute.

This range and variation in stroke rates was satisfactory during the period that shapers were primarily "special" machines and were employed almost solely for tool room purposes. Recently, however, this type of machine tool has been so perfected that it is now recognized as a "manufacturing" machine capable of turning out work at a rate commensurate with present day quantity production.

To better adapt this type of machine tool to quantity production and to increase the efficiency of the machine in its various uses this invention proposes an improved transmission between the prime driver and the ram reciprocating element whereby the stroke range will be extended and the number of available speeds will be materially increased. With my improved transmission it becomes possible in a so-called standard machine to reciprocate the ram at any one of sixteen speeds varying from approximately 7½ to 118 strokes per minute, from a single speed in the prime driver.

This invention further proposes the construction by means of which the sixteen speeds may include a minimum speed of one stroke per minute and a maximum speed of approximately 118 strokes per minute.

Another object of the invention is so to construct and arrange the additional mechanism adapted to extend the stroke range and increase the number of speed changes that it may be incorporated in conventional machines without interfering with the usual speed change gearing and the table rapid traverse train.

Still another object is so to combine the speed change mechanism with a main control clutch located at the user's side of the machine that both the clutch unit and the speed change gearing carried thereby readily may be removed from the main frame of the machine to permit certain speed change gears, carried by the clutch unit, to be removed and replaced by others having a different ratio, thereby to produce different combinations of the sixteen available speed changes. This latter is of particular advantage to the manufacturer of the machine, inasmuch as it enables him to build standard shaping machines in large numbers and later readily to modify a machine to meet the specific demands of any customer who might require other than standard speeds.

Decided advantages are attained by locating the main control clutch and the table rapid traverse train at the user's side of the machine as distinguished from prior machines in which those elements were located at the side remote from the user. Among the advantages attained are the simplification of the connections between the clutch actuating lever and the rapid traverse control lever, which necessarily must be at the user's side, and the mechanism actuated by those levers, and the elimination of the extra and undesirable rods, links, lever, etc. which otherwise would be required to extend to the opposite side of the machine.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, 5 drawings depicting a preferred typical construction have been annexed as a part of this disclosure and, in such drawings, like characters of reference denote corresponding parts throughout all the views, of which:—

10 Figure 1 is a side elevation of a shaping machine embodying the present invention, as viewed from the user's side thereof. Fig. 2 is a diagrammatic development of the power transmission for reciprocating the ram and 15 for propelling the work-table. Fig. 3 is a disassembled detailed view of a removable sub-housing and certain interchangeable gears associated therewith, showing how said parts may be removed from the machine to 20 permit the interchange of said gears with other gears having different ratios. Fig. 4 is a detailed view showing a modified driving connection between the main drive shaft and the gears on the clutch unit. Fig. 5 is a left hand elevation of the gears shown in Fig. 4.

Referring more specifically to the drawings, this invention is disclosed as embodied in a shaping machine comprising a main housing 1 which supports, at its forward end, 30 the usual work-table 2 and upon which is reciprocably mounted the usual tool-ram 3. As in conventional shaping machines, the ram is given its reciprocatory movements by means of a rocker-arm 4 actuated by a crankpin 5 adjustably supported upon a bull-wheel 6.

The table 2 is propelled horizontally beneath the ram by means of a nut 7 threaded upon a rotatable screw 8. This screw is adapted to be rotated selectively at either a slow rate, to effect feeding movements of the table, or at a rapid rate, to effect rapid traverse movements of the table, by means later to be described. The transmission for rotating the bull-wheel, and thereby the crankpin 5, includes a shaft 9 journaled in the main housing transversely of the path of reciprocation of the ram. Splined upon the shaft 9 are two gear units 10 and 11 affording, respectively, gears 10^a—10^b and gears 11^a—11^b adapted to be meshed selectively with gears 12, 13, 14 and 15 rotatably mounted on a shaft 16 also supported in the main housing. These gears comprise a speed-change mechanism designated generally as B and serve to multiply by four each of the speeds received from the shaft 9. Fixed to the gear 12 is a gear 17 which meshes with, and drives a gear 18 forming a part of the shiftable gear-unit 19 which also affords a gear 20. The gear-unit 19 is translatably mounted on a shaft 21 supported by the main housing and the gears 18 and 20 thereof are adapted selectively to be meshed with gears 22 and 23 of the bull-wheel. The gears 18, 20, 22 and

23 comprise a speed-change mechanism designated generally as C, which serves to multiply by two each of the speeds received from the speed-change mechanism B. The foregoing describes conventional means for transmitting to a bull-wheel of a shaping machine 70 8 speeds from a single speed of a shaft journaled in the main housing. As hereinbefore stated, the present invention provides in addition to the above described speed changes, means whereby as many as 16 speeds may be 75 transmitted to the bull-wheel. This has been accomplished by the provision of an additional speed-change mechanism designated generally as A and which later will be described. 80

Power to reciprocate the ram and to propel the work-table may be provided by any suitable prime driver, such, for example, as an electric motor P or a driving pulley P' (as indicated in Fig. 2), connected to a main drive shaft D journaled in the main housing, transversely thereof. The shaft D is preferably connected with the prime driver by a separable coupling E which permits the removal of one type of prime driver and the 90 substitution thereof by another type of driver. As shown in Fig. 2, the two-speed speed-change mechanism A, between the drive shaft D and the shaft 9, comprises a shiftable gear-unit 24 splined to the free end of the drive shaft. The gear-unit 24 comprises gears 25 and 26 adapted selectively to be meshed with complementary gears 27 and 28 removably secured upon a main clutch element 29 rotatably journaled on the shaft 9. A second 95 main clutch element 30 splined to the free end of the shaft 9 serves, upon manipulation of lever L located in the user's side of the machine, to lock the clutch element 29 to the shaft 9, thereby to cause the shaft to be rotated at either of two speeds as may be determined by the selective engagement of the gears 25 and 27 or 26 and 28. A gear-shifter 31 fixed upon a slide rod 32, having a hand-grasp 33 located at the user's side of the machine, serves to shift the gear-unit 24 on a shaft D, selectively to engage the gears 25 and 27 or 26 and 28. The speed-change mechanism A and the main control clutch are mounted within a sub-housing 34 removably secured upon the main housing at the user's side of the machine. The sub-housing may be removed at will to permit removal of the gears, 25, 26, 27 and 28 and replacement thereof by similar gears of different size, thereby 110 to vary the ratios between the driving and driven gears which will, in turn, vary all of the speeds transmitted to the ram. 115

Feeding movements of the work-table are effected from the ram-reciprocating means 125 and in time relation therewith. For this purpose a cam 35 fixed upon the rotary hub 6' of the bull-wheel serves to push outwardly, always to the same extent, a rack-plunger 36. An associated stationary cam 37 (set by a 130

hand wheel H) serves to limit the retreat of said rack-plunger. The amplitude of stroke of the rack-plunger is thus determined. A gear train, comprising gears 38, 39 and 40, of 5 which the first is actuated by the rack-plunger, operates a pawl-carrier 41 carrying a pawl 42 which engages a ratchet wheel 43 adapted to be clutched to a rotatable shaft 44. Actuation of the pawl effects, through the ratchet 10 wheel 43, the shaft 44 and other connections later to be described, intermittent rotations of the feed screw 8 which, in turn, effects step-by-step movement of the work table.

Means also is provided for rotating the 15 screw 8 at a rapid rate, thereby to effect rapid traverse movements of the work-table. This means comprises a sprocket 45 fixed to and rotating with the clutch element 29. A sprocket chain 46 connects the sprocket 45 20 with a similar sprocket 47 which rotates through gears 48, 49, 50 and 51 a clutch element 52 rotatably journaled on the shaft 44. A clutch spool 53, splined to the shaft 44 and actuated by a lever 54 at the operator's side 25 of the machine serves selectively to engage either the clutch element 52 or a similar clutch element formed on the hub of the ratchet wheel 43, thereby to connect to the shaft 44 either the gear 51, to effect rapid 30 traverse of the table, or the ratchet 43, to effect slow feed thereof. Bevel gears 55 and 56 convey the feed or traverse to a common shaft 57 carrying at its forward end a bevel gear 58 which drives at its diametrically opposite sides, bevel gears 59 and 60 rotatably journaled on an un-threaded portion 8' of 35 the screw 8. A clutch-spool 61 splined to the portion 8', and actuated by a lever 62, serves selectively to connect either a gear 59 or the 40 gear 60 to the table-propelling screw 8.

Figs. 4 and 5 show a modified construction of gearing embodied in the removable sub-housing whereby the speed of rotation transmitted to the bull-wheel and consequently the 45 speed of reciprocation of the ram may be as slow as one actuation per minute. In this construction the gear 25, provided by the gear-unit 24 splined to the drive shaft, is adapted to be meshed with a larger gear 65 50 carried upon a stub shaft 66 journaled in the sub-housing 34. A pinion 67 rotatable with the gear 65 meshes with and drives an internal gear 68 fixed to the clutch element 29.

The other gear 26 of the gear unit 24 is 55 adapted to be engaged with the gear 28 on the clutch element 29, as hereinbefore described. It is to be understood that the modification shown in Fig. 4 is adapted to replace the speed change mechanism A shown in Fig. 2 60 and to combine with the speed change mechanisms B and C and the feed and rapid traverse trains for the work table. Inasmuch as it is obvious how this replacement may be effected further illustration and description 65 thereof is deemed unnecessary.

Throughout this specification the term "user's side" has been employed. By that term is meant that side of the machine at which are located the feed-rate changer, the shifter from feed to power-traverse, the direction reverser and the operating hand-grasps therefor.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of United States:—

1. In a shaping machine including a main housing, a sub-housing secured thereto, a ram reciprocable thereon, a prime driver, a main drive shaft in said housing extending transversely of the path of reciprocation of said ram and rotated by said prime driver, and means including a rotary crank and an oscillating rocker-arm actuated thereby for reciprocating said ram; a transmission including three serially arranged sets of selectively operable change gears affording, respectively, 90 two, four and two speed changes between said main drive shaft and said ram-reciprocating means for transmitting to the latter sixteen speeds from a single speed in the main drive shaft, one of said sets of change gears being 95 arranged within said sub-housing and being adapted to be removed and replaced by another set having a different ratio thereby to vary the speeds transmitted to ram-reciprocating means.

2. In a shaping machine including a main housing, a ram reciprocable thereon, means including a rotary crank and an oscillating rocker-arm actuated thereby for reciprocating said ram, a main drive shaft journaled in said housing, and a second shaft journaled in said housing transverse to the path of reciprocation of said ram; a multiple speed power transmission connecting said second shaft with said ram-reciprocating means; a multiple speed power transmission including a plurality of sets of selectively engageable driving and driven gears of varying ratios mounted, respectively, on the main drive shaft and said second shaft, the driving gears being non-rotatable relative to the drive shaft and the driven gears being rotatable on the second shaft; and a clutch mechanism mounted on said second shaft for securing thereto said driven gears.

3. In a shaping machine including a main housing, a ram reciprocable thereon, means including a rotary crank and an oscillating rocker-arm actuated thereby for reciprocating said ram, and a main drive shaft and a second shaft journaled in said housing transverse to the path of reciprocation of said ram; a multiple speed power transmission connecting said second shaft with said 10 ram-reciprocating means; a clutch-unit secured to said housing exteriorly thereof; a clutch element carried by said clutch-unit and rotatably journaled on said second shaft; two driven gears of unequal diameter 15 secured to said clutch element; a second clutch element non-rotatably secured to said second shaft; means to effect a driving connection between said clutch elements; a gear unit splined to said main drive shaft 20 and affording driving gears complementary to the driven gears on said clutch element; and means selectively to mesh said complementary driving and driven gears to transmit to said second shaft two speeds from a single 25 speed in the drive shaft.

4. In a shaping machine including a main housing, a ram reciprocable thereon, a prime driver located at one side of the machine, and means including a rotating crank and 30 an oscillating rocker-arm actuated thereby for reciprocating said ram; a power transmission, including three serially arranged speed change devices, connecting said prime driver with said crank for rotating the latter at any one of more than ten speeds from 35 a single speed in the prime driver; and manually actuatable levers located at a side of the machine remote from that at which the prime driver is located for selectively actuating each of said speed change devices.

5. In a shaping machine including a main housing, a ram reciprocable thereon, means to reciprocate said ram; a work table movable horizontally beneath said ram, and a driven shaft journaled in said housing transverse to the path of reciprocation of said ram; first and second multiple-speed power transmission for actuating said ram-reciprocating means from said driven shaft; 45 a prime driver; a third multiple-speed power transmission between said prime driver and said driven shaft, said first, second and third multiple-speed transmissions being serially arranged and adapted to transmit to said 50 ram-reciprocating means more than ten speeds from a single speed in the prime driver; a main clutch on said driven shaft for controlling the flow of power thereto from said prime driver; table propelling means; a slow speed transmission operated from said ram-reciprocating means for actuating said table propelling means at a feeding rate in synchronism with the movements of said ram; a rapid transmission operable independently of said ram-recipro-

cating means for actuating said table propelling means at a rapid traverse rate; and means selectively to render effective either said feed or traverse transmission.

6. In a shaping machine including a main housing, a ram reciprocable thereon, means including a rotary crank and an oscillating arm actuated thereby for reciprocating said ram, and a main drive shaft and a second shaft journaled in said housing transverse to the path of reciprocation of said ram; a multiple-speed power transmission connecting said second shaft with said ram-reciprocating means; a sub-housing removably secured to said main housing exteriorly thereof at the user's side of the machine; a clutch element carried by said sub-housing and rotatably journaled on said second shaft; two driven gears of unequal diameter removably secured to said clutch element and replaceable by others of different size; a second clutch element non-rotatably secured to said second shaft; means to effect a driving connection between said clutch elements; a gear unit splined to a free end of said main drive shaft 80 and affording driving gears complementary to the driven gears on said clutch element; said gear unit being removable from said main drive shaft for replacement by a similar unit providing gears of different size; and means selectively to mesh said complementary driving and driven gears to transmit to said second shaft two speeds from a single speed in the drive shaft.

7. In a shaping machine including a main housing, a ram reciprocable thereon, means to reciprocate said ram, a sub-housing removably secured to said main housing, and a main drive shaft; a power transmission including a driven shaft and a plurality of 100 serially arranged sets of speed change devices between said main drive shaft and said ram reciprocating means; one of said speed change devices being arranged in said sub-housing, and comprising a driving gear unit 105 splined to said drive shaft and providing two gears; two gears rotatably journaled on said driven shaft of which one is adapted to be meshed with one of the gears of said driving unit; clutch means for engaging with said driven shaft the gears thereon; an intermediate gear unit providing one gear adapted to be engaged by one of the gears of said driving unit, and another gear permanently in mesh with the other gear rotatably journaled on said driven shaft; and means to shift said driving gear unit.

8. A ram reciprocating mechanism for shaping machines comprising a rocker arm operatively connected with the ram; a rotatable bull-wheel connected to oscillate said arm; a prime driver; a driving connection between said prime driver and said bull-wheel, including three sets of serially arranged multiple speed change gears each in- 125 130

cluding selectively operable gears for transmitting to said bull-wheel more than ten speeds of rotation from a single speed in the prime mover; a master clutch for determining the action or inaction of the ram, said master clutch and the gears of one set being arranged in a removable casing located at one side of the machine, the gears of that set being removable and replaceable by another set of different ratio.

In witness whereof, I have hereunto subscribed my name.

WILLIAM F. ZIMMERMANN.
